UNITED STATES PATENT OFFICE.

DELMER H. MOORE, OF GREENVILLE, MICHIGAN.

CLEANING DEVICE.

1,335,451.

Specification of Letters Patent. Patented Mar. 30, 1920.

Application filed September 21, 1916. Serial No. 121,376.

To all whom it may concern:

Be it known that I, DELMER H. MOORE, a citizen of the United States, residing at Greenville, in the county of Montcalm and State of Michigan, have invented new and useful Improvements in Cleaning Devices, of which the following is a specification.

The present invention relates to cleaning devices; and its object is to provide a device of that character whereby the surface to be cleaned may be washed by brushing or rubbing while wet, water being directed to portions of such surface which lie outside the area to which the brush is being applied at the moment, and this in order that all the dirt particles which may be dislodged by the brush may by the water thus directed be rinsed and carried away; and further, to provide improved methods for constructing such cleaning devices, and means for detachably securing their parts together. This object and any other objects herein-after appearing are attained by, and the invention finds preferable embodiment in, the illustrative structure hereinafter described and illustrated by the accompanying drawings in which:

Figure 1 is a view in perspective of a cleaning device;

Fig. 2 is a transverse section of the same taken on a plane corresponding to line 2—2 of Fig. 1;

Fig. 3 is a fragmentary view of the underside thereof; and,

Fig. 4 is a transverse section of the same taken on a plane corresponding to line 4—4 of Fig. 1, but showing the brush bristles replaced by longitudinally extending strips, as of rubber, let into the brush back.

In the embodiment of the invention chosen for detailed description in the body of this specification and for illustration by the drawings, the body 1 is of sheet metal and its edge portions 2, 3, 4, 5 are turned over downwardly and inwardly and brought up to the under side of said body to provide a continuous water pipe 6, the joints at said under side and at the corners being made water tight as by soldering. Water is supplied to this pipe through a suitable flexible tube 7 communicating with such pipe through the connection 8 which may be provided with a cock 9, and is discharged from orifices 10 through the pipe's wall, being thereby directed against the surface to be cleaned, and to such portions of said surface

as lie outside the area to which the brush is applied at the moment. Especially where the device is to be used in cleaning walls, windows and other vertical surfaces, the part 60 of the pipe to which the water is first admitted through the tube (being that part formed by the turned over edge portion 2) need not be provided with orifices, because when the device is held upright on the pole 65 handle 11, water discharged from orifices in said part of the pipe would be of slight practical advantage and therefore waste. The brush 12 which may be of suitable brushing or rubbing material, as bristles 70 13 shown in Figs. 1, 2 and 3, rubber strips 14 shown in Fig. 4 or the like, is for ready replacement longitudinally slidable between retaining flanges 15 carried by and extending downwardly inwardly from the brush-holding member 16 which is detachably secured to the middle portion of the body 1 and surrounded by the pipe, as by screw bolts 17 extending through said member and body. The end portions 3, 5 of the 80 pipe, extending downwardly as they do from the under side of the body, afford means to prevent the sliding disengagement of the brush from the brush-holder in the assembled position of the parts; and yet the 85 nuts 18 of the screw bolts being turned off the parts may be readily disassembled and a worn brush replaced by a new one.

It will be seen that as the device is passed over the surface to be cleaned, the water 90 discharged from the orifices in the portion 4 above the brush and from the portions 3, 5 at either side thereof, rinse and carry away all the dirt particles which the brush has dislodged; so that, the brush itself can 95 not leave on the surface any dirt particles which may have clung to it. A suitable handle 19 is carried by the body 1.

The invention being intended to be defined solely by the claims, is not to be limited to or by details of construction shown or described.

I claim:

1. In a device of the character described; a body having a water pipe disposed on its 105 periphery, the pipe having orifices through its wall; a brush; a brush-holding member having oppositely disposed downwardly inwardly extending flanges adapted to slidably receive and hold the brush; means for 110 detachably securing said member to the body's middle portion; and means for caus-

ing water to flow through the pipe and out of the orifices.

2. In a device of the character described; a body having a water pipe disposed on its periphery, the pipe having orifices through its wall; a brush; a brush-holding member having oppositely disposed downwardly inwardly extending flanges adapted to slidingly receive and hold the brush; means for 5 detachably securing said member to the body's middle portion; means for holding the brush against sliding movement on said member; and means for causing water to flow through the pipe and out of the orifices.
- 10 3. In a device of the character described; a body having a continuous water pipe disposed around its periphery and on its under

side, the pipe having orifices through its wall; a brush; a brush-holding member having oppositely disposed downwardly inwardly extending flanges adapted to slidingly receive and hold the brush; screw bolts for detachably securing said member to the middle portion of the body's under side; and means for causing water to flow 25 through the pipe and out of the orifices.

In testimony whereof I have hereunto set my hand in presence of two subscribing witnesses, this 15th day of September, A. D. 1916.

DELMER H. MOORE.
